UNITED STATES PATENT OFFICE.

JOHN B. VAN HOUTEN, OF NEWARK, NEW JERSEY.

DESIGN FOR AN EAR-RING.

SPECIFICATION forming part of Design No. 14,862, dated March 4, 1884.

Application filed November 21, 1883. Term of patent 7 years.

To all whom it may concern:

Be it known that I, JOHN B. VAN HOUTEN, a citizen of the United States, residing at Newark, in the county of Essex and State of New Jersey, have invented and produced a certain new and original Design for Ear-Rings; and I do hereby declare the following to be a full, clear, and exact description of the invention, such as will enable others skilled in the art 10 to which it appertains to make and use the same, reference being had to the accompanying drawings, and to letters of reference marked thereon, which form a part of this specification.

15 Figure 1 is a front elevation, and Fig. 2 a side elevation, these figures being deemed sufficient to fully illustrate the design.

The leading feature of the design consists in the configuration of the pendent portion there- 20 of. Said pendant is centrally band-shaped, as

at *a*, laterally adjacent to which, as at *bb*, the same is concavo-convex or bowl-shaped, the convexity being toward the band-shaped portion *a*. At the lower part of the pendant the band-shaped portion *a* projects downward 25 from the annular part thereof and widens laterally, as at *c*, the edges of the widened portion being irregular or dentate when viewed in front elevation.

I claim—

The design for an ear-ring, consisting of an ear-ring having the pendent portion thereof shaped substantially as shown and described.

In testimony that I claim the foregoing I have hereunto set my hand this 16th day of 35 November, 1883.

JOHN B. VAN HOUTEN.

Witnesses:

CHARLES H. PELL,
F. F. CAMPBELL.
